WATER CLOSET

Bjorn R. Kristoffersen, Kirkland, Wash., assignor to
The Boeing Company, Seattle, Wash.

Filed Sept. 18, 1975, Ser. No. 614,572

Term of patent 14 years

Int. Cl. D23—02

U.S. Cl. D23—67

Fig. 1

Fig. 2

Fig. 3

Fig. 4

Fig. 5

Fig. 6

FIG. 1 is a perspective view of a water closet showing my new design, with the cover in an open position; FIG. 2 is another perspective view thereof, showing

the seat and cover in an open position;

FIG. 3 is a third perspective view thereof, showing the seat and cover in the closed position;

FIG. 4 is a front elevational view of FIG. 3;

FIG. 5 is a side elevational view of FIG. 3; and

FIG. 6 is a top plan view of FIG. 3.

We claim:

The ornamental design for a water closet, as shown.
